UNITED STATES PATENT OFFICE.

HOWARD G. MACDONALD, OF WILKINSBURG, PENNSYLVANIA, ASSIGNOR TO WESTINGHOUSE ELECTRIC AND MANUFACTURING COMPANY, A CORPORATION OF PENNSYLVANIA.

CIRCUIT-INTERRUPTER.

1,189,274.

Specification of Letters Patent.

Patented July 4, 1916.

Application filed February 15, 1912. Serial No. 677,865.

To all whom it may concern:

Be it known that I, HOWARD G. MACDONALD, a citizen of the United States, and a resident of Wilkinsburg, in the county of Allegheny and State of Pennsylvania, have invented a new and useful Improvement in Circuit-Interrupters, of which the following is a specification.

My invention relates to circuit interrupters and it has special reference to automatic tripping devices for this class of apparatus, whereby the interrupters may be released under predetermined circuit conditions.

The object of my invention is to simplify and improve the construction and operation of devices of the above-indicated class and to provide reliable and adequate means for automatically releasing the operating mechanisms thereof.

It has been customary in the prior art to provide an electromagnet for the purpose of releasing the latch which restrains the operating mechanism of a circuit interrupter in its closed position and, under the usual operating conditions, such an arrangement operates satisfactorily. However, in certain cases where it is found desirable to adjust the tripping mechanism to release the interrupter at a predetermined low current, sufficient energy is not imparted to the electromagnet to overcome the frictional resistance between the heavy parts of the operating mechanism and the restraining latch.

According to my present invention, I overcome the difficulty above referred to and accomplish a reliable and positive release of the interrupter by means of an auxiliary power device which is normally restrained in its set position and which may be automatically released by the usual tripping magnet to forcibly actuate and release the main latch of the interrupter. Moreover, the relative proportions and the arrangement of parts is such that, although considerable energy, which is available for tripping purposes, is stored in the power device, an exceedingly small amount of energy is required to effect its release.

My invention may best be understood by reference to the accompanying drawing of which—

Figure 1 is a view, partially in side elevation and partially in section, of a portion of a circuit interrupter which embodies my invention and Fig. 2 is a detail plan view

of parts of the operating mechanism embodied in my invention.

Referring to the drawing in detail, the device here shown comprises a plurality of stationary and movable contact members 1 and 2, an operating mechanism 3 for the movable members 2, a latch 4 for said operating mechanism, an operating handle 5, an auxiliary power device 6 and a tripping magnet 7.

The stationary contact members 1 are supported at the lower ends of suitable bushings 8, which are adapted to protect and insulate the main conducting members (not shown) from the casing or cover 9 of a tank 10 in which the coöperating contact members 1 and 2 are immersed in oil. The movable contact members 2 are suitably supported upon a cross arm 3^a, in the usual manner, said cross arm 3^a being attached to the lower end of a rod 11. The coöperating contact members 1 and 2 are preferably of the usual butt-contact type, although any other suitable construction may be employed.

The operating mechanism 3 comprises a lever 12, one end of which is pivotally connected to the upper end of the rod 11 and the other end of which is pivotally connected to the upper end of a guiding link 13, said link 13 being pivotally mounted upon a shaft 14 which is carried by a bracket member 15 pertaining to the cover 9. The link 13 projects a short distance below its pivotal support 14 and is provided with a lug or projection 16, for a purpose to be hereinafter set forth.

A toggle for operating the movable contact members 2 comprises a link 17 which is pivotally connected to the lever 12 at a point substantially midway between its ends, and an arm 18 constituting an integral part of a lever member 19 which is also mounted upon the shaft 14. A guiding link 20, which is pivotally connected to the lever 12 and to the upper end of a standard 21, serves to constrain the movements of the operating mechanism within prescribed limits.

Integrally associated with the lever 19 and its arm 18, is a projecting member 22 that is provided with an adjustable stop 23 to coöperate with the projecting portion 16 of the link 13, whereby the pressure between the coöperating contact members 1 and 2 may be adjusted to any desired value.

A lever 24 is fixed to the shaft 14 and its

free end is provided with the latch 4 having a catch 25 to engage a pin 26 in the end of the lever 19, whereby the lever 19 and the lever 24 are normally locked together to operate as a single unit. In order to restrain the levers 19 and 24 in their closed position, a latch 27 is provided which is pivotally mounted upon a pin 28 that is carried by a suitable bracket member 29, and said latch 27 is provided with a catch 30 to engage a suitable detent 31 that is secured to the lever 24, substantially midway between its ends.

Integrally associated with the latch 27, is a projection 32 having a recess 33 to receive a spring 34 which is disposed therein and acts against a flange 35 of the supporting bracket 29 in order to maintain the catch 30 in engagement with the detent 31. Furthermore, the latch 27 is provided with an extension member 36 which projects between the respective arms of a bifurcated portion 37 that is provided intermediate the ends of the lever 19. A pin 38 projects between the arms of the bifurcated portion 37 just referred to, and engages the extension member 36 when the interrupter is closed. The extension member 36 serves as a cam during the opening operation of the interrupter and, by reason of its peculiar shape and its engagement with the pin 38, the release of the catch 30 from the detent 31 is effected when the lever 19 moves to its upper position, as will be hereinafter more fully set forth.

The operating handle 5 is preferably located outside of a casing 39 which envelops and protects the operating mechanism 3 and the auxiliary power device 6, and is rigidly secured to the shaft 14, while a counterweight 40 is rigidly connected to said shaft by means of an arm 40^a to bring the operating handle 5 and the lever 24 to their upper positions when the interrupter is released.

The auxiliary power device 6 comprises a bell crank lever 41 that is pivotally mounted upon a pin 42 and a coil spring 43, the ends of which are respectively connected to the upper end of an arm 44 of the bell crank lever 42 and to a projecting member 45 which constitutes a part of the supporting bracket 29. The free arm 46 of the bell crank lever 41 has a pin and slot connection 47 with a rod or striking member 48 that is located beneath an arm 49 of the main latch 4 and is adapted to actuate the same.

The bell crank lever 41 is restrained in its set position by means of a latch 50 having an arm 51 to be engaged by a striking member or rod 52 that is associated with a movable core member 53 of the electro-magnet 7, said magnet being also provided with a stationary core member 54 and an exciting winding or coil 55, in accordance with the usual practice.

It will be noted that the main arm 44 of the bell crank lever 41 and the coil spring 43 are disposed approximately in a line, the one with the other, so that the bell crank lever 41 may be regarded as restrained in approximately its "dead center" position. Hence, although considerable energy may be stored in the spring 43, the bell crank lever 41 may be restrained in its set position and released therefrom by an exceedingly small amount of energy. Manifestly, when the bell crank lever 41 and the spring 43 are released, the lever arm through which the spring 43 acts, rapidly increases so that the striking member 48 is projected with considerable force against the arm 49 of the latch 4, whereby a positive release of the lever 19 is effected.

In order to reset the auxiliary power device 6 during the opening operation of the interrupter, a link 56 is provided, the lower end of which is pivotally connected to the upper end of the bell crank lever 41, while the upper end thereof has a pin and slot connection 57 with the lever 24. In order to permit of manual tripping of the interrupter, a tripping rod 58, having a handle or button 59, is provided, and is so located with respect to the latch 27 that said latch may be manually operated when desired.

Assuming the various parts of the interrupter to occupy the position shown, manual release may be accomplished in the manner hereinafter described.

The rod 58 is first pushed upwardly, thereby engaging the latch 27 and withdrawing the catch 30 from the detent 31. Thus, the operating mechanism is released and the operating toggle, comprising the link 17 and the arm 18, is allowed to collapse, thereby permitting the separation of the co-operating contact members 1 and 2 by reason of the action of gravity. During the opening operation of the interrupter, the levers 19 and 24, which are still locked together by the latch 4, as well as the operating handle 5, are moved upwardly in a clockwise direction, to their upper positions, as indicated in dot and dash lines. No movement of the bell crank lever 41, however, is effected during this operation by reason of the lost-motion or pin and slot connection 57 which has already been referred to. In order to reset the interrupter, it is only necessary to move the handle 5 downwardly, thereby forcing the operating toggle, comprising the link 17 and the arm 18, into its set position and thus raising the movable contact members 2 into co-operative engagement with the stationary contact members 1. When the associated levers 19 and 24 are in their lower positions, the latch 27 again serves to restrain them, as hereinbefore set forth.

Assuming that sufficient current traverses

the exciting coil 55 of the electromagnet 7 to energize said magnet, the automatic tripping operation of the interrupter is effected as follows: When the movable core member 53 is actuated, it moves the set or striking member 52 against the arm 51 of the auxiliary latch 50, which normally restrains the power device 6 in its set position. Thus, the bell crank lever 41 is released and the 10 spring 43 acts to cause a clockwise rotative movement of said bell crank lever, thereby forcibly projecting the striking member 48 against the arm 49 of the latch 4. Upon the withdrawal of the latch 4 from the pin 26, the lever 19 is released and a collapse of the 15 operating toggle, heretofore referred to, is effected, whereby the cooperating contact members 1 and 2 are disengaged and the lever 19 is moved to its upper position. During the upward movement of the lever 19, the latch 27 is withdrawn from the detent 31 that is associated with the lever 21, by reason of the engagement of the pin 28 with the extension member 36 of said latch. 20 The counterweight 40 then carries the lever 24 and the handle 5 to their upper positions where they are again associated with the lever 19, by reason of the latch 4. During the upward movement of the lever 24, the bell crank lever 41 is raised into its normal set position by means of the connecting link 36, so that the power device 6 is immediately reset after its automatic operation and is adapted to accomplish its intended purpose. 25 At the moment the interrupter is again closed. Obviously, the power device 6 may also be so constructed as to embody a weight or other suitable means, in place of the spring 43. Since the closing operation of the interrupter, subsequent to its automatic release, is identical with that hereinbefore described, no further explanation of the same will be given.

For illustrative purposes, I have shown and described my invention as employed in connection with a circuit interrupter of a particular type and of specific structural details, but I do not wish to be restricted in this respect, as my invention, broadly considered, may be adapted for any class of circuit interrupters. Furthermore, modifications in the structural details and in the arrangement and location of parts of the tripping device hereinbefore set forth which do not materially change the operation thereof, should be understood as included within the spirit and scope of my invention.

I claim as my invention:

1. In a circuit interrupter, the combination with cooperating stationary and movable contact members, an operating mechanism for said movable members, and means for restraining said operating mechanism, of a pivotally mounted bell crank lever having a recess therein, a spring attached to

one of the arms of said lever having the recess therein and acting approximately in a line therewith, a latch adapted to engage the recess to restrain said lever, a striking member to release said restraining means, 70 said striking member being operatively connected to the free arm of said lever, and an electromagnet for releasing said latch.

2. In a circuit interrupter, the combination with cooperating stationary and movable contact members, an operating mechanism for said movable members, and means for restraining the said operating mechanism, of a pivotally mounted bell crank lever having a recess therein, a spring attached to the arm of the lever having the recess therein, means adapted to engage the recess in the lever to restrain the said lever, a striking member for releasing said restraining means, said striking member being operatively connected to the free arm of the said lever, and electro-responsive means for releasing the said means that engages the recess.

3. In a circuit interrupter, the combination with relatively movable cooperating contact members, an operating mechanism for the movable members, a compound operating lever associated with the said mechanism and comprising main and auxiliary levers, means for latching said levers together, means for restraining said compound lever in its closed position, means operatively related to a portion of the compound lever for automatically releasing the restraining means subsequent to the release of the latching means, and an electro-responsive device for automatically tripping said latching means, of means associated with said compound lever for resetting the 100 electro-responsive device during the automatic opening of the interrupter.

4. In a circuit interrupter, the combination with cooperating stationary and movable contact members, an operating mechanism therefor embodying a compound operating lever comprising two relatively movable pivotally mounted arms, a latch for restraining one of said arms, a second latch on said arm for locking both arms together, and means on said second arm for releasing said first latch, of a power device for releasing said second latch, electro-responsive means for tripping said power device, and means associated with said power device and said first arm for resetting said power device.

5. In a circuit interrupter, the combination with cooperating stationary and movable contact members, an operating mechanism for said movable members, and means for restraining said operating mechanism, of a pivotally mounted bell crank lever, means associated with one of the arms thereof for actuating said lever, a latch for

restraining said lever, a striking rod operatively associated with the free arm of said lever by a pin and slot connection for releasing said restraining means and electro-responsive means for releasing said latch.

- 5 6. In a circuit interrupter, the combination with cooperating stationary and movable contact members, an operating mechanism for said movable member embodying
10 two pivotally mounted relatively movable operating levers, and means for restraining said operating mechanism, of a pivotally mounted bell crank lever means associated

with one of the arms thereof for actuating said lever, a latch for restraining said lever, 15 a striking rod operatively connected to the free arm of said lever for releasing said restraining means, and electro-responsive means for releasing said latch.

In testimony whereof, I have hereunto 20 subscribed my name this 13th day of Feb. 1912.

HOWARD G. MACDONALD.
